UNITED STATES PATENT OFFICE.

EVAN M. DAVIES, OF NORTH TONAWANDA, NEW YORK.

FOLDING TABLE.

1,366,637.

Specification of Letters Patent. Patented Jan. 25, 1921.

Application filed November 24, 1919. Serial No. 340,101.

To all whom it may concern:

Be it known that I, EVAN M. DAVIES, a citizen of the United States, residing at North Tonawanda, in the county of Niagara 5 and State of New York, have invented new and useful Improvements in Folding Tables, of which the following is a specification.

This invention relates to a folding table 10 which is very light and strong and capable of being folded very compactly so that the same can be conveniently transported when camping or touring with an automobile.

It is the object of this invention to provide a table which possesses these requirements and which can be manufactured at comparatively low cost.

In the accompanying drawings:

Figure 1 is a side elevation of my improved folding table. Fig. 2 is a bottom plan view of the same. Fig. 3 is an end view of the same. Fig. 4 is an end view of the table top in its folded condition. Fig. 5 is a fragmentary vertical transverse section, 25 on an enlarged scale, taken on line 5—5, Fig. 1. Fig. 6 is a horizontal section taken on line 6—6, Fig. 5, looking upwardly and omitting the table top. Fig. 7 is a fragmentary vertical section taken on line 7—7, 30 Fig. 5. Figs. 8 and 9 are fragmentary vertical sections taken on the correspondingly numbered lines in Fig. 3.

Similar characters of reference indicate corresponding parts throughout the several 35 views.

The table top in its preferred form comprises two leaves or sections 10, 10, which are constructed of beaver board or similar strong, light and thin material which takes 40 up little space. The top sections are pivotally connected at their opposing longitudinal edges by hinges 11 or other means, so that the same may be unfolded into a position in which the leaves or sections are in 45 the same horizontal plane, as shown in Figs. 1—3, or the same may be folded together with their undersides opposing each other, as shown in Fig. 4.

For the purpose of strengthening or stiffening these top sections, each of the same 50 is provided on its underside adjacent to its outer longitudinal edge with a longitudinal cleat 12 which is of channel or U-shaped form in cross section and secured to the top 55 by means of rivets 13 passing through the top and the web or body of the cleat, as

shown in Figs. 2—5. The cleat on one of these table tops is preferably arranged a different distance from the pivotal connection between the top sections than the cleat on the other top section, so as to permit these cleats to clear and pass each other when folding the table top, as shown in Fig. 4, and thus enable the part to be arranged more compactly at this time. 60

14, 14, represent two bolsters or cross pieces which are detachably secured to the underside of the table top sections adjacent to opposite ends of the same when they are unfolded and serve as part of the means 70 for supporting the top when the table is to be used. Each of these bolsters is preferably constructed of an angle iron which has a horizontal flange 15 engaging with the underside of the top sections and a vertical 75 flange 16 depending from the outer edge of the horizontal flange. The means for detachably securing the bolsters to the top sections may be varied but this is preferably accomplished by providing the top sections at their corresponding ends with pairs of buttons 17, each pair projecting downwardly through a pair of vertical openings 18 in the horizontal flanges of one of the 80 bolsters, and a pair of catches or hooks 19 pivoted on the underside of said horizontal flange by rivets 20 or otherwise, and detachably engaging their beaks 21 with the respective buttons on a line below the horizontal flange of the bolster. Each of the 85 buttons may be variously constructed, but as shown in Fig. 7, the same preferably comprises a screw 22 arranged in an opening in the table top and bearing with its head against the upper side of the table top, a 90 washer 24 arranged on this screw and engaging with the underside of the table, and an internally threaded screw sleeve 23 engaging with the lower end of said screw and provided at its lower end with an annular 95 flange 25. When the beak of a catch engages with the contracted neck formed by the sleeve 23 it is held thereon by the washer 24 and flange 25 against displacement 100 lengthwise of the button and holds the parts 105 in an assembled position. The buttons 17 on one leaf or section of the table top are preferably arranged out of line from the corresponding buttons on the other top section when the top sections are folded, thereby avoiding interference between the same, 110 as shown in Fig. 4.

Underneath each of the bolsters is arranged a pair of legs 26, 27 which in their operative position are unfolded and cross each other about midway of their length in a direction crosswise of the table. These legs may be made of wood or any other suitable strong light material and the members of each pair are pivotally connected at the point of crossing between the same by a hollow thimble 28 passing through corresponding openings in the pair of legs and having the external flanges 29 at its opposite ends engaging the outer sides of said legs. One of the legs, say the leg 26, of each pair is pivotally connected at its upper end to the vertical flange of the respective bolster adjacent to one end thereof by means of a rivet 30, so that this leg and the bolster can be folded and unfolded. The other leg 20 of each pair is detachably connected with the other end of the bolster preferably by providing this leg with a headed screw or button 31 which projects through a horizontal opening 32 in the vertical flange of the respective bolster and a catch or hook 33 pivoted at one end by a rivet 34 to the leg 27 and engaging its beak 35 with this button, said leg and catch engaging with opposite sides of the vertical flange of the 30 bolster when the parts are assembled.

In order to insure stability of the table, means are provided for connecting the two pairs of legs with each other, which means comprise a longitudinal reach 36 and a pair 35 of diagonal braces 37. The reach is preferably constructed in the form of an iron rod and the same has its externally screw threaded ends arranged in the thimbles 28 of both pairs of legs and secured thereto by 40 inner and outer screw nuts 38, 39 arranged on each end of the reach and engaging with the inner and outer sides of a pair of legs, as shown in Fig. 9. The two braces preferably cross each other lengthwise of the 45 table and each is constructed of an iron rod. The ends 40 of each brace rod are arranged horizontally and secured in horizontal openings 41 formed in corresponding legs of both pairs by means of inner and outer 50 screw nuts 42, 43 applied to each end of a brace and engaging with the inner and outer sides of the respective leg, as shown in Fig. 8. When the braces are in place one end of 55 each brace is connected with the upper end of one leg of one pair which supports one

end of the top while the opposite end of this brace is connected with the lower end of a leg of the pair which supports the other end of the top. By this means the legs are detachably connected with each other and 60 with the top which permits the table to be quickly set up for use or knocked down and folded compactly for storage or transportation. When set up the table is very strong and able to sustain the weight of such articles which are likely to be placed upon the same.

I claim as my invention:

1. A folding table comprising a top, bolsters each having horizontal and vertical flanges and engaging its horizontal flange with the underside of said top and provided with vertical openings, buttons arranged on the underside of said top and projecting downwardly through said openings, horizontally swinging catches mounted on said bolsters and engaging with said buttons, and legs connected with the vertical flange of each of said bolsters. 70 75

2. A folding table comprising a top, a plurality of bolsters each having horizontal and vertical flanges, the horizontal flanges being detachably secured to the underside of said top and each of the vertical flanges being provided with a horizontal opening, a plurality of pairs of legs, the members of each pair having their central parts crossing each other and pivotally connected while the upper end of one of said legs engages with one side of one of said bolsters and is 90 provided with a horizontal button projecting through the horizontal opening in the respective bolster, and a vertically swinging catch mounted on the leg having the button and arranged on the opposite side of said bolster and engaging with the button on the leg which carries the respective catch. 95

3. A folding table comprising a top, bolsters detachably mounted on the underside of said top, a plurality of pairs of legs, each pair crossing each other with their central parts and having their upper ends movably connected with one of said bolsters, flanged thimbles pivotally connecting the crossed parts of each pair of legs with each other, and a longitudinal reach arranged at its opposite ends in the thimbles of said legs and provided with screw nuts engaging with opposite sides of said thimbles. 100 105

EVAN M. DAVIES.
